UNITED STATES PATENT OFFICE.

FREDERICK W. HERMAN, JR., OF SALINA, KANSAS.

HIGH CHAIR.

1,238,767.

Specification of Letters Patent.

Patented Sept. 4, 1917.

Application filed April 15, 1916. Serial No. 91,309.

To all whom it may concern:

Be it known that I, FREDERICK W. HERMAN, JR., a citizen of the United States, residing at Salina, in the county of Saline and 5 State of Kansas, have invented a new and useful Improvement in High Chairs, of which the following is a specification.

My invention relates to an improvement in high chairs in the nature of an adjustable 10 seat, and the object thereof is to so construct the seat that the chair may be adapted for the use of children varying in age from about six months to two or more years.

Generally, the mother begins to place her 15 infant in an ordinary high chair when it reaches the age of six months; and a girdle is placed around it to hold it securely to the back of the chair, and the seat being of considerable depth, and the infant being 20 short in limb the lower extremities of the child, from the waist downward, rest in a horizontal position for it is impossible for the child to bend its knees so as to drop the lower legs over the edge of the seat. Such 25 forced position is uncomfortable and unwise for it causes an unnatural strain upon the muscles and has a tendency to interfere with the natural and proper development of the spinal column. The same kind of chair 30 continues to be used until the child attains the age of two or more years, and during all that time the child is denied freedom of movement of its limbs while occupying the chair which cannot fail to retard the development thereof during such time.

To overcome this serious objection to the present construction of the ordinary high chair I have devised what I term, an adjustable seat therefor.

40 A child six months old should be provided a chair the seat whereof is of less depth than that required for a child of two or more years, and the chair devised by me is so constructed that it provides as comfortable 45 a seat for a child of six months as it does for a child of two years, for it permits the child to sit in an upright position with its knees bending over the edge of the seat.

I attain this object by the mechanism illustrated in the accompanying drawings, in which—

Figure 1 is a front elevation of a chair showing my invention, one section of the seat being lowered to position for use by a 55 child six months old.

Fig. 2 is a side elevation of the same.

Fig. 3 is a front elevation showing the movable section raised to a horizontal position for use by a child two or more years of age.

60 Fig. 4 is a view of the underside of the seat showing the two sections hinged together, and the spring-catches which lock them in a horizontal plane.

Similar numerals refer to like parts 65 throughout the several views.

In the present instance the seat is composed of two transverse sections, front and back sections, one fixed and the other movable, which I have designated as 1 and 2, 70 respectively.

Section 1 is rigidly secured to the chair frame and section 2 is movably affixed to section 1 at or near the meeting edges of the two sections by hinges 3. It will be 75 noted that these hinges are affixed to the underside of both sections and are set back from the edge of section 1 so that when section 2 is dropped to a vertical position for use, the face of said section will be flush with 80 the inner edge of section 1.

The foot-rest for the ordinary high chair is generally secured to the front legs as at 4 and projects forward therefrom. As said foot-rest is not adapted for use with my improvement when in the positions shown in Figs. 1 and 2, I have provided a foot-rest 5 which is secured between the two front legs of the chair and extends backward. At the rear edge of foot-rest 5 is secured stop 6 90 against which the front section, 2, bears when lowered to a vertical position.

The two sections of the seat are provided on the underside with spring catches 7, the movable section carrying the male portion 95 and section 1 carrying the female portion, in such relation as to co-act when section 2 is raised to a horizontal position to be locked to section 1.

In the accompanying illustrations I have 100 not shown the table or tray that usually forms part of a child's chair, for it has no relation to my invention.

It is believed that the operation and use of the instant invention will be clear from 105 the foregoing description of parts and relations, and further detailed explanation thereof is accordingly omitted.

My invention as shown and described herein is my preferred form for carrying 110

out my invention, but as this construction is susceptible of modification and variation without departing from the spirit or sacrificing any of the advantages of my invention, it is intended that all matters contained in the above description or shown in the accompanying drawings shall be interpreted as illustrative and not in a limiting sense.

10. It is also to be understood that the language used in the following claims is intended to cover all of the generic and specific features of the invention herein described and all statements of the scope of the invention, which as a matter of language might be said to fall therebetween.

What I claim as my invention and desire to secure by Letters Patent, is—

1. In a device of the character described, 20 a seat composed of two sections, one rigidly secured to the chair frame and the other movable in a vertical direction.

2. In a device of the character described, 25 a seat having a cut-out portion hinged thereto and adapted to be lowered to a vertical position.

3. In a device of the character described, a seat composed of two sections in combina-

tion with means for varying the depth of the seat.

4. In a device of the character described, 30 a seat having a cut-out portion hinged thereto and adapted to drop perpendicularly to shorten the seat, and means for releasably securing said cut-out portion to the fixed 35 portion of the seat in a horizontal plane.

5. In a device of the character described, 40 the combination of a chair frame, a seat composed of two sections one rigidly secured to the frame, the other adapted to be moved in a vertical direction, and two foot- rests attached to said frame and projecting in opposite directions in horizontal planes.

6. In a device of the character described, 45 a seat composed of two sections, one rigidly secured to the chair frame and the other movable in a vertical direction and having a free front edge.

7. In a device of the character described, 50 a seat composed of two sections, one rigidly secured to the chair frame, the other movable in a vertical direction and having a free front edge, and means for locking the two sections in same horizontal plane.

FREDERICK W. HERMAN, JR.
